(57) **CLAIM**

The ornamental design for a health-regain device, as shown and described.

DESCRIPTION

FIG. 1 is a perspective view of a health-regain device showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown in the figures are included for the purpose of illustrating portions of the health-regain device and form no part of the claimed design.
